(57) **CLAIM**

We claim the ornamental design for a projector system, as shown and described.

DESCRIPTION

FIG. 1 is a front perspective view of a projector system according to the present invention.

FIG. 2 is a rear perspective view thereof; and,

FIG. 3 is a bottom view thereof.

The broken lines shown in the drawings are for illustrative purposes only and form no part of the claimed design.

The shading lines shown in the drawings represent the approximate three-dimensional contour of the design, and are not intended to indicate surface decoration.
